UNITED STATES PATENT OFFICE.

HARRY LANDSIEDEL, OF NORWOOD, OHIO, ASSIGNOR TO THE DALTON ADDING MACHINE COMPANY, OF CINCINNATI, OHIO, A CORPORATION OF OHIO.

ADDING, CALCULATING, AND RECORDING MACHINE.

Application filed June 28, 1920. Serial No. 392,416.

To all whom it may concern:

Be it known that I, HARRY LANDSIEDEL, a citizen of the United States, residing at Norwood, Hamilton County, and State of Ohio, have invented a new and useful Adding, Calculating, and Recording Machine, of which the following is a specification.

This invention relates to adding, calculating and recording machines.

For convenience of illustration and description, I have shown my present invention embodied in an adding machine of the Dalton type. The Dalton adding machine, as shown in the drawings, comprises recording mechanism for recording or listing items or numbers which are involved in the calculations or additions performed by the machine. My present invention is not limited as to its usefulness or design to embodiment in a Dalton adding machine, nor in a machine containing recording mechanism, but my invention may be usefully employed in adding or calculating machines of a type without recording mechanism.

My present invention comprises mechanism which may be designated generally or broadly as mechanism for subtracting a number from another number or total of greater numerical value previously placed or set up in the adding or calculating mechanism of the machine. While my improved subtracting mechanism may be referred to as such, the process of subtraction involves the placing or introduction into the machine of the complement of the number or item which is to be subtracted from the number or total previously set up or placed in the machine. In a machine containing my invention the operation of subtracting one number or item from a number or total previously set up or placed in the machine is performed by setting up or introducing the complementary number into the differential mechanism of the machine, and then setting the subtraction mechanism for operation, and then operating the machine. As a result of this the various mechanisms of the machine are co-ordinated and cooperated so that the full complement of the number or items to be subtracted, including as many 9s as may be necessary to extend to the highest numerical order within the capacity of the machine, is introduced into the adding mechanism, thereby causing carrying or transferring from order to order as will be readily under-

stood, with the result that after such operation the desired number or item has been subtracted from the number or total in the adding mechanism, thereby setting the adding mechanism to represent the correct amount or number.

It often occurs that in operating the machine to list a series of items, one or more items may be listed erroneously and added or included in the calculations performed by the machine. In such instances the item or items listed and included in the addition or calculations through error may be subtracted, thus correcting the error. In such case it is desirable to designate the item or items subtracted so that it may be known at a glance that such items are not included in the calculations listed, but were listed through error and subsequently corrected. My invention comprises means for designating the items subtracted by printing a designating character adjacent to each such item. The mechanism for printing such distinguishing character is arranged to operate automatically as an incident to the operation of the machine to subtract.

My invention also comprises mechanism cooperating with the recording mechanism of the machine for preventing record being made of the complement number which is used to correct a previous error. This mechanism is under control of the mechanism by which the subtracting operations are performed and is required to operate automatically at the desired time.

Since no record of the complementary number is made, it is desirable to prevent operation of the paper feed or line space mechanism during the subtracting operation. My invention comprises mechanism for effecting that result so that the uniformity of line spacing of the listed items is maintained, irrespective of the fact that the complementary number used in a subtracting operation is not listed.

An object of my present invention is to provide mechanism of the character and operable to perform the results and functions above mentioned, as well as other desirable results and functions, which will be apparent to those skilled in the art from a reading of the following description taken in connection with the accompanying drawings, in which—

Fig. 1 is a side elevation of a Dalton add-

110

ing machine containing my present invention, the case of the machine and a few of the shafts and frame parts being in section.

Fig. 2 is a similar elevation viewed from 5 the opposite side.

Fig. 3 is a plan view of a part of the mechanism of the machine showing in particular the differential mechanism and the means for controlling a part of the differential mechanism to permit movement of the operating racks for the adding mechanism to introduce complementary 9s into the adding mechanism in subtracting operations.

Fig. 4 is an elevation showing the connections for printing a designating character to designate the subtrahend items, and also for controlling the adding rack in the lowest numerical order as required to add 1 in units order to complete the complementary number as required to render the operation of subtraction proper. In this view of the drawings the mechanism is shown in its idle position.

Fig. 5 is a view showing the same mechanism in operative position.

Fig. 6 is a view of the subtracting key and its connections in their operative positions.

Fig. 7 is a similar view of the subtracting key and its connections before operation 30 thereof.

Fig. 8 is a view showing the mechanism for preventing operation of the line spacing or paper feed mechanism.

Fig. 9 shows an example of the work in 35 subtracting that may be performed by the machine.

The Dalton adding machine in which I have chosen to illustrate the invention comprises a set of numeral keys 1 secured upon 40 key levers 2 and arranged in convenient manner in a key board. The items or numbers struck on the numeral keys are thereby set up in the differential mechanism 3 which, as is known, in the Dalton adding machine,

45 comprises digit stops arranged in rows in numerical order in a movable carriage. After each item or number has been set up or represented in the differential mechanism the type-carriers 4 and their associated racks 50 5 are operated in the usual way to list or print the numbers on paper fed to the recording type by operation of paper feed mechanism comprising a platen 6 and actuating devices therefor described generally further on in this specification, and to introduce or add the numbers in the adding mechanism. The type supported by the type-carriers are driven by appropriately mounted hammers 7 as required to list the

60 numbers on the paper fed to the type by the platen 6. The hammers are pivotally supported upon a shaft 8 and are driven against the type at the proper time by springs 9 arranged appropriately for that 65 purpose. Each of the hammers is formed

with a latch arm 10 arranged to be engaged as required to hold the same in retracted position by a hook 11 on a releasable latch member. The latch members also have arms 12 which are engaged by projections 13 (Fig. 8) on the type-carriers with which said latch members respectively correspond when the type-carriers are at rest in their normal or idle positions. Thus, the latch members for the hammers are held in their lower positions as shown in Fig. 8 in opposition to the tendency of their springs 14 to raise the rear ends of the latches. When any one or more of the type-carriers are moved to recording position the projections 13 on such type-carriers as move to recording position are carried away from and out of contact with the arms 12 of the corresponding latches, thus permitting such latches to be raised by their springs 14 a sufficient distance to place shoulders 15 on the raised latches in front of a latch release bar or bail 16. The latch release bar or bail 16 has one end pivoted upon a stationary support 17 (Fig. 3) and its opposite end connected with a lever 18 beyond the opposite side of the series of latches, so that said latch bar extends entirely across and above the series of latches. The lever 18 is pivoted upon a support 19 and has an arm carrying a roller 20 (Fig. 8) operating upon a cam 21. The cam 21 is carried by an arm 22 secured upon the main shaft 23 of the machine. The upper end of the lever 18 is actuated rearwardly by a spring 24 and in the normal or idle position of the machine said lever is held in its forward position by the cam 21 in opposition to the spring 24. When the lever 18 is in its forward position, as shown in Fig. 8, the bar 16 is above the shoulders 15, so that the latches cannot rise to place the shoulders 15 in front of said bar 16.

For present purposes it is sufficient to know that the main shaft 23 of the machine is turned in a forward direction by means of an operating handle 25 (Fig. 3) or otherwise, after each number is set up in the differential mechanism, in order to permit the proper type-carriers to advance to proper recording position. Such forward turning movement of the shaft 23 advances the cam 21 to position to permit the spring 24 to move the upper end of the lever 18 rearwardly as required to move the latch release bar 16 rearwardly a sufficient distance to permit the shoulders 15 of the latches whose type-carriers have advanced to rise in front of the latch bar. After the shaft 23 has completed its forward turning movement it is turned rearwardly to its starting point, thereby causing the cam 21 to operate the lever 18 which moves the latch release bar 16 forwardly, thus disengaging the latches which had been engaged with said 130

- latch bar from their corresponding hammers 7 and permitting the hammers to be operated by their springs 9 as required to drive the type to print.
- 5 While the printing mechanism per se does not constitute a part of the present invention, the same being the subject-matter of a separate application Serial No. 357,776, eventuating in Patent No. 1,395,121, dated 10 October 25, 1921, filed February 11, 1920, my present invention includes means hereinafter described for preventing release of latches by the latch bar 16 when the machine is used in subtracting operations.
- 15 The Dalton adding machine also includes a series of adding pinions 26 arranged to cooperate with the racks 5 in the usual way in adding, transferring and clearing operations. The racks are operated in a rearward 20 direction, as usual, by springs 27 (Figs. 1 and 5) as required to transfer from lower to higher numerical orders. Said racks when not operating in clearing operations are stopped in their normal or idle positions by 25 lugs 28 thereon engaging the hooked ends of the carrying or transfer pawls 29 which are raised in the usual manner from the position shown in Fig. 1 to the position shown in Fig. 5 in transferring operations.
- 30 The transferring operations in the Dalton adding machine are well known and do not require further description. My invention comprises means arranged to operate at the proper time to raise the carrying or trans- 35 fer pawl 29 in the lowest or units numerical order to permit the rack which operates the units adding pinion to move rearwardly, as though a transferring operation was taking place in connection with the units adding pinion, as required to complete the introduc- 40 tion into the adding mechanism of the full complement of the subtrahend or item which it is desired to subtract from the number or total that had previously been set up or repre- 45 sented in the adding mechanism. This means which is comprised within my invention is hereinafter described.
- The Dalton adding machine also comprises mechanism for operating the platen 6 to move the paper in line spacing. As 50 shown, the actuating mechanism for the platen comprises a ratchet wheel 30 (Fig. 1) on the platen shaft arranged to be engaged by a pawl 31. The pawl 31 is pivotally sup- 55 ported upon an arm 32 secured to a rock shaft 33. A lever 34 is slidably supported upon a polygonal portion of the shaft 33, extends downwardly, and is actuated in a forward direction by a spring 35. Forward 60 movement of the lever 34 turns the shaft 33 in a direction to engage the pawl 31 with the ratchet wheel 30 so that when the lever 34 is moved back to its normal or starting position the pawl 31 first turns the platen, there- 65 by moving the paper the distance of a line
- space, and then disengages from the ratchet wheel, there being a lateral extension 36 on the pawl engaging under the arm 32 thereby holding the pawl in a position in opposition to its spring 37.
- 70 The Dalton adding machine includes mechanism for effecting the above described operation of feeding the paper in line spacing automatically and as an incident to the operation of the shaft 23. Such mechanism 75 comprises an arm 38 (Fig. 8) attached to the shaft 23 and connected by a link 39 with a bell crank lever 40. One arm of the bell crank lever 40 in the idle or normal position of the machine engages a roller 41 on the 80 arm 34 and thereby holds said arm in its rearward position in opposition to the spring 35 as clearly shown in Fig. 8. When the shaft 23 is turned in a forward direction the lever 40 is moved to the position in which 85 it is shown in broken lines in Fig. 8, thereby permitting the spring 35 to operate the arm 34, turn the shaft 33, and engage the pawl 31 with the ratchet wheel 30. As the shaft 33 is turned toward its starting point the lever 90 40 operating against the roller 41 forces the arm 34 to its starting position, causing the pawl 31 to turn the platen and thereby move the paper a line space. My present invention comprises means for preventing opera- 95 tion of the line spacing mechanism when the machine is used in subtracting operations.
- The foregoing comprises a general de- 100 scription of the co-ordinated mechanism of an adding, calculating and listing machine with which my invention directly cooperates. While I have described the co-ordinated mechanism of a Dalton adding machine it will, of course, be apparent that my invention is not restricted as to its use, design and 105 capability to a machine of that particular kind; but it will be apparent that my invention may be used with equal advantage in other machines.
- 110 As previously mentioned, my invention comprises mechanism for rendering the machine practicable for use in subtracting operations. The invention includes mechanism for effecting the completion of the introduc- 115 tion into the adding or calculating mechanism of the complete complement of the subtrahend; that is when any number or item is to be subtracted from a number or total previously set up or introduced into the adding or calculating mechanism of the machine, 120 such subtracting operation is effected by the introduction of the complete complement of that number into the adding mechanism, thus throwing or taking out of the adding mechanism the subtrahend number. In case 125 the invention is used in a listing machine my invention embodies means for preventing listing of the subtrahend number or complement and also for preventing movement of the paper in line spacing, though it will be 130

understood that such portions of the invention may be omitted when the machine in which the invention is used is not a listing machine. I contemplate the use of the invention in machines of the non-listing type, and claim the invention as new whether extended to a listing machine or whether the parts that co-operate with the listing mechanism be present or not.

10 When it occurs that any item has been erroneously listed and included within the addition or calculations and such error is not discovered until after the completion of the listing and calculating operation of the machine, the error may be corrected by use of this invention. In such case the complement of the item erroneously listed and included within the additions and calculations is introduced into the differential mechanism of the machine by operation of the complementary numeral keys; with the exception that the digit in units order lacks 1 of being of sufficient value, and with the further exception that the 9s in the higher numerical orders, above the highest numerical order of the subtrahend, need not be struck on the keys but will be automatically introduced into the calculation. After the complementary number to the extent mentioned is introduced into the differential mechanism the subtraction controlling device or key is operated as required to cause the mechanism of the present invention to function, after which the main shaft of the machine is operated in the usual way, and as a result thereof the error is corrected; and in the case of a listing machine, the subtrahend number or item in the list of items is appropriately designated by the printing of a character adjacent thereto for that purpose.

As shown the subtraction controlling device or key comprises a key 42 upon an appropriately formed lever 43 pivotally mounted on a shaft 44. The key lever 43 is held in its raised position by an appropriately connected spring 45 which is connected with the lever in such a way as to return the lever to its raised position at the proper time. The subtracting key lever is held in its depressed or operative position as long as required by a latch device comprising a projection 46 on the lever which engages under a shoulder 47 formed on a latch member 48, when the lever is in its depressed position as shown in Fig. 6. A spring 49 connects the key lever 43 with the pivoted latch 48 so as to cause proper releasable latch engagement between said parts when the key lever is depressed.

60 The latch 48 is supported upon a pivot 50 and has an extension 51 in the line of movement of an arm 52 (Fig. 8) on the rock shaft 23. As a result of this construction and arrangement the latch will hold the lever 43 in its depressed position until the shaft 23

reaches the final operation of its forward turning movement. Just before the shaft 23 completes its forward turning movement the arm 52 on said shaft engages the extension 51 of the latch member and releases the latch, thereby permitting the lever 43 at the proper time to be raised to its normal position by its spring 45. As a result of the depression of the lever 43 the mechanisms of the present invention are caused to function when the shaft 23 is operated. I will now describe the means by which the full complement of the subtrahend is utilized to correct the error resulting from entering into the calculating and listing the erroneous item.

In the example shown in Fig. 9, the item 2457 was entered into the calculations and listed through error. This item should not have been entered into the calculations and should not have been listed. In order to correct the error and remove this item from the calculations the complementary number for the number 2457, less 1, is set up in the differential mechanism by operation of the numeral keys in the usual way, after which the key lever 43 is depressed and latched in its depressed position, following which operation the machine is operated as though any ordinary item was being added and listed. The complementary number of the number 2457, less 1, is 7542 and, therefore, the number 7542 is set up in the differential mechanism. After the complementary number has been set up in the differential mechanism the key lever 43 is depressed, causing an arm 53 on said lever 43 to raise an arm 54 which is attached to a rock shaft 55 and which has a pin 56 engaging the arm 53. The rock shaft 55 supports an arm 57 from which a link 58 leads to the lower arm of a lever 59 which is pivotally mounted on a support 60. The upper arm of the lever 59 is pivotally connected with the forward end of a link 61, and the rear end of said link 61 is pivoted to an arm 62. The arm 62 is in connection with a plate 63 having projections extending into slots or openings in a support 64, whereby said arm 62 is pivotally supported. The arm 62 extends downwardly and forwardly above the usual stop or abutment plate 65 found in the Dalton adding machine for preventing operation of the type-carriers and racks above the highest numerical order of the number or item being used in any calculation.

In order to make complete correction of the number or item 2457, which had been erroneously entered into the calculations and listed, it is necessary to enter into the correcting calculation a 9 in each numerical order above the highest numerical order of the number that had been erroneously used. To permit the type-carriers and racks in the higher numerical orders to operate it is 130

necessary to press the abutment plate 65 out of the way of the shoulders 66 on the racks 5. To effect this depression of the abutment 65 in order to permit operation of the 5 type-carriers and racks in higher numerical orders, as required to employ the necessary number of 9s, the arm 62 is extended above the plate 65 in such a way that when the key lever 43 is depressed and the connections 10 therefrom are operated, the arm 62 will press the plate 65 downwardly from the position shown in Fig. 7 to the position shown in Fig. 6. In the position shown in Fig. 6 the plate 65 is out of the way of the 15 shoulders 66 leaving the type-carriers and racks in higher numerical orders free to move to recording position when the machine is operated. In this way the necessary number of 9s are taken care of in the higher 20 numerical orders, so as to clear the machine of the error.

As previously stated, it is necessary to enter into the calculation in units order a digit which is the full complement of the 25 digit in units order in the error item. That is, it is necessary to enter into the calculation in units order a digit which added to the digit in units order in the error makes 10, so as to transfer 1 from units order to 30 tens order, and transfer 1 from tens order to hundreds order, and transfer 1 from hundreds order to thousands order, and so on throughout the full capacity of the machine which, obviously, takes out or throws 35 out and thereby corrects the error. As previously mentioned the number 7542, which had been set up in the differential mechanism as complementary to the error, lacks 1 in units order of being the full complement 40 of the error number. To complete the full complement 1 is added into units order automatically and as an incident to operation of the machine in a subtracting operation, so as to make the full complement of the 45 error number. I will now describe the mechanism by which 1 is added into units order to make the full complement required.

In order to permit the transfer of 1 into units order in addition to the digit set up 50 in units order in the complement number as required to complete the full complement, the transfer pawl 29 in units order is raised from the usual position shown in Fig. 1 to the position shown in Fig. 5 to permit 55 the units rack, which operates the units adding pinion, to move rearwardly as though a transferring operation was taking place from a lower numerical order, as in case of addition of fractions, in an example 60 of addition. The device for raising the transfer pawl 29 for the units rack comprises a bell crank lever 67 pivoted on a support 68 and having a projection 69 on one arm thereof extending under the transfer 65 pawl 29 that is provided for the units

rack. In order to raise the transfer pawl 29 controlling the rack in units order it is only necessary to operate the lever 67. For this purpose I provide an actuator 70 which, in case the invention is employed in an adding, calculating and listing machine, may be a type-carrier used to carry special type for printing designating characters such, for instance, as characters indicating a clear condition of the machine, a character for 75 designating items that had been listed by error, etc. As shown, the actuator 70 is a type-carrier and carries special type 71 for printing designating characters and arranged to be driven by a special one of the 80 hammers 7. The actuator 70 supports a projection 72 which may be caused to engage with and operate the lever 67 as required to raise the transfer pawl 29 controlling the units rack. The actuator 70 85 is held from operation when the machine is being operated in ordinary adding and calculating operations not involving subtraction or other special operations. For preventing operations of the actuator 70 beyond a slight extent of movement a projection 73 is provided on said actuator and arranged to engage a shoulder 74 on a pivotally supported stop member 75. As shown (Fig. 4) the projection 73 and the stop 74 90 are arranged relative to each other in order to permit slight movement of the actuator 70 which, in the form shown, is a type-carrier. Provision is made for this movement in order to permit the type-carrier to 95 move far enough to place the uppermost type thereon in proper position relative the printing line. Such movement of the actuator 70 is insufficient to cause operation of the lever 67. In order to cause operation 100 of the lever 67 as required to raise the transfer pawl 29 in units order, it is necessary to move the pivoted stop member 75 to place a shoulder 76 on said stop member in position to be engaged by the projection 73. 105 Such movement of the actuator 70 is sufficient to cause the projection 72 to operate the lever 67, resulting in the raising of the transfer pawl 29 in units order and permitting the rack in units order to be moved 110 rearwardly by its spring 27 a distance sufficient to carry or to transfer 1 into units order. This will complete the introduction into the calculation of the full complement of the item that had been erroneously entered into the calculation and listed.

The stop member 75 is moved to adjusted position to permit movement of the combined type-carrier and actuator 70 as shown, to trip the transfer pawl 29 and to position the proper type for printing a designating character adjacent to the erroneous item, as an incident to operation of the key lever 43. An arm 77 (Figs. 4 and 5) in connection with the key lever 43 extends be- 115 120 125 130

hind a projection 78 on a link 79 so that when the key lever is operated the link 79 will be moved in a forward direction. The forward end of the link 79 is supported by a pin and slot construction 80, and the rear end of said link is pivoted to a depending arm in connection with the stop member 75. The stop member 75 is thereby operated from the position shown in Fig. 4 to a position in which the shoulder 76 is in the line of movement of the projection 73, thus permitting the actuator and type-carrier 70 to move to the position shown in Fig. 5. When the key lever 43 is released from the latch member 48 as before described and returns to its normal position, the link 79 and the stop member 75 are returned to their normal positions. Means for effecting the return of the link 79 and the stop member 75 to their normal positions is shown, the same comprising a spring 81 (Fig. 4) connecting the link with a stationary part.

As before stated the latch release bar 16 is held in position to prevent the shoulders 15 on the hammer latches from rising in front of the latch bar whenever the machine is operated to perform subtraction. The latch release bar is held from movement during the subtracting operation by a retaining device or abutment comprising a bifurcated member 82 embracing the latch release bar 16 between the arms thereof (Figs. 2, 5 and 6) and having its rear end pivotally connected with the upper arm of the lever 59. As before explained and as clearly shown in Fig. 5, the upper arm of the lever 59 is moved to and held in a forward position by the depression of the key lever 43. Such forward movement of the upper arm of the lever 59 is sufficient to hold the latch release bar 16 from movement when the machine is operated to perform subtraction. Since the normal or idle position of the latch release bar 16 is above the shoulders 15 it follows that the shoulders cannot rise in front of the release bar, when the type-carriers move as required to perform the subtracting operation before described. As a consequence of this printing of the complementary number of the error item is automatically prevented. However, the latch for the hammer cooperating with the type-carrier 70 is released at the proper time during the subtracting operation in order to effect printing of the designating character 83 (Fig. 9) adjacent to the item that had been erroneously entered into the calculation and listed, in order to give visual indication of the fact that such item has been taken out of and excluded from the calculation.

The means for preventing operation of the paper feed or line space mechanism is also operated as an incident to the use of the machine in a subtracting operation. Said means 65 comprises a device for preventing movement

of the lever 34 (Figs. 1, 2 and 8) far enough to engage the pawl 31 with the ratchet wheel 30. As shown, said device comprises an arm 84, which may be a part of the lever 59. The arm 84 is provided with a part 85 which is moved into line of movement of a projection 86 on the lever 34, thus stopping movement of said lever 34 short of the position in which the pawl 31 may be engaged with the ratchet wheel 30. Since the pawl does not engage the ratchet wheel the platen will not be turned and the paper will not be moved, but will be held stationary.

From the foregoing it will be seen that my invention comprises mechanism for conveniently performing subtracting operations by use of an adding and calculating machine, involving the process of adding the complementary numbers of the items that had been erroneously entered into the calculations. The invention is complete to that extent when used in a non-listing machine. However, when the invention is used in a listing machine the invention also comprises mechanism for preventing printing of the complementary numbers and for preventing the line spacing of the paper during the process of subtraction, including means for printing a designating character adjacent to the erroneous items.

I contemplate such variation of the invention as may adapt it for use in different types of machines and do not restrict myself to unessential features or limitations.

What I claim and desire to secure by Letters Patent, is:—

1. In a machine of the character described, the combination of type-carriers, type on said type-carriers, spring actuated hammers for driving the type on said type-carriers to print, a latch for holding each of said hammers in a retracted position, a bail device for releasing latches corresponding to the type-carriers in recording position, and means for preventing effective operation of said bail device, leaving all latches holding corresponding hammers when any of the type-carriers operate irrespective of the positions to which the type-carriers move.

2. In a machine of the character described, the combination of type-carriers, type on said type-carriers, spring actuated hammers for driving the type on said type-carriers to print, a latch for holding each of said hammers in a retracted position, a movable bar for releasing all latches corresponding to the type-carriers in recording positions, mechanism for moving said bar, and a settable device for preventing effective movement of said bar and thereby preventing release of any latches corresponding to operated type-carriers when any of the type-carriers operate.

3. In a machine of the character described, the combination of type-carriers movable to

- and from recording positions, type on said type-carriers, hammers for driving the type on the type-carriers to print, latches for holding the hammers retracted, a bail device 5 for releasing the latch members from the hammers corresponding to the type-carriers in recording positions, means for moving said device and said latch members as required to effect engagement between the 10 latch members and said device, and means for preventing engagement of any of said latch members and said device which would enable said device to release said latch members as desired, when the type-carriers are 15 operated in subtracting operations as described. 4. In a machine of the character described, a series of type driving hammers, a series of latches for holding said hammers in retracted positions, a bar, a stationary support to which said bar is pivoted, means for moving selected ones of said latches into position to be engaged by said bar, a lever for oscillating said bar to release said latches from 20 said hammers, and means for preventing operation of said bar from releasing said hammers. 5. In a machine of the character described, a series of type driving hammers, a series of latches for holding said hammers in retracted positions, shoulders on said latches, a pivoted bar, means for moving selected ones of said latches into position to enable said bar to engage said shoulders, mechanism for 25 operating said bar to release said latches from said hammers after said latches have been moved as aforesaid, and means for preventing operation of said bar to release said latches from said hammers. 6. In a machine of the character described, a series of type-carriers movable to and from recording positions, type on said type-carriers, a stop member for preventing movement of said type-carriers, connections for 30 moving said stop member to position to permit the type-carriers to move to recording positions, hammers for driving the type on said type-carriers to record, latches for holding said hammers retracted, a movable bar 35 for releasing said latches from said hammers, and means controlled by said connections for preventing said bar from releasing said latches from said hammers, when said connections are in position to permit the 40 type-carriers to operate. 7. In a machine of the character described, a series of type-carriers movable to and from recording positions, type on said type-carriers, a stop member for preventing movement of said type-carriers, a lever for 45 moving said stop member to position to permit the type-carriers to operate, connections for operating said lever, a series of hammers for driving the type on said type-carriers 50 to record, latches for holding the hammers retracted, a swinging bar for releasing the latches from the hammers, and a device controlled by said connections that operate said lever for preventing said bar from releasing the latches from the hammers. 8. In a machine of the character described, the combination of a series of type driving hammers, movable latches for holding said hammers retracted, a bar extending across all of the latches for releasing varying numbers of said latches from said hammers, an abutment for preventing effective movement of said bar, and means for moving said abutment to and from position in which it will prevent effective movement of said bar. 9. In a machine of the character described, the combination with type driving hammers, latches for holding the hammers in retracted positions, a bar extending across all of the latches for moving varying numbers of said latches to release said hammers, and mechanism for operating said bar to release varying numbers of said latches from said hammers, of an abutment movable to and from position to prevent effective operation of said bar, a lever for moving said abutment, and manipulative connections for operating said lever. 10. In a machine of the character described, the combination with type driving hammers, latches for holding the hammers in retracted positions, a bar for moving said latches to release said hammers, and mechanism for operating said bar to release said latches from said hammers, of an abutment movable to and from position to prevent effective operation of said bar, a lever for moving said abutment, manipulative connections for operating said lever, and a latch device for holding said connections and thereby said lever to retain said abutment in position to prevent effective operation of said bar. 11. In a machine of the character described, a series of type driving hammers, latches holding said hammers retracted, a support, a bar extending across all of the latches and having one end pivoted on said support, a lever connected with the opposite end of said bar, means for operating said lever and thereby said bar to release said latches from said hammers, and means for preventing effective operation of said bar to prevent said bar from releasing said latches as desired. 12. In a machine of the character described, a series of type driving hammers, latches holding said hammers retracted, type movable to and from position to cooperate with said hammers, a stop for preventing movement of said type to position to cooperate with said hammers, connections for moving said stop to position to permit the type to move to cooperate with the hammers, a bar for releasing the latches to permit the

hammers to operate, means for moving said bar to release said hammers, and means controlled by said connections for preventing effective movement of said bar.

- 5 13. In a machine of the character described, a series of type-carriers, type on said type-carriers, a stop for preventing movement of said type-carriers, a lever for moving said stop to position to 70
10 permit the type-carriers to operate, key mechanism, connections from said key mechanism to said lever for operating said lever by said key mechanism, hammers for cooperating with the type on the type-carriers to 75
15 record, automatic means for operating said hammers as an incident to operation of the type-carriers, and means controlled by said connections for preventing operation of said hammers.
- 20 14. In a machine of the character described, a series of type driving hammers, a series of latches holding said hammers retracted, a stationary support, a bar extending across the series of latches and having 80
25 one end pivoted on the stationary support, a lever in connection with the opposite end of said bar, mechanism for operating said lever and thereby said bar to release the latches from the hammers, and means for 85
30 preventing effective operation of said bar.

15. In a machine of the character described, a series of type-carriers, type on said type-carriers, a series of type driving hammers for cooperating with the type on 90
35 the type-carriers to record, a series of latches holding the hammers retracted, a stationary support, a bar extending across the series of latches and having one end pivoted on the stationary support, mechanism 95
40 for oscillating the opposite end of said bar for releasing the latches from the hammers corresponding with the type-carriers which operate, and means for preventing effective operation of said bar by said mechanism and thereby preventing release of the 100
45 latches from the hammers when the type-carriers operate.

16. In a machine of the character described, a series of type driving hammers, a series of 110
50 latches for holding the hammers retracted, a bar extending across the series of latches, mechanism for operating said bar to release said latches from said hammers, and a device for holding said bar from operation 115
55 to prevent effective movement of said bar by said mechanism.

17. In a machine of the character described, type-carriers, type on said type-carriers, hammers for driving the type on 120
60 the type-carriers to record, latches holding said hammers retracted, a bar operable to release said latches from said hammers, means for operating said bar, a platen, means for operating said platen to feed paper to receive the records from the type on said type- 125
65

carriers, a lever, means for operating said lever, and devices operated by said lever to prevent said bar from releasing said latches and to prevent operation of said platen.

- 70 18. In a machine of the character described, the combination with a revoluble platen for feeding paper, a pawl for rotating said platen in line spacing, a lever for operating said pawl, type for printing on 75
the paper on said platen, hammers for driving the type to print, latches holding the hammers retracted, a bar for releasing said latches, and means for operating said bar to release said latches, of a key lever, a 80
device operated by said key lever to prevent effective operation of said bar and thereby preventing release of said latches, and a device operated by said key lever for preventing operation of said first-named lever 85
to operate said pawl.

- 90 19. In a machine of the character described, a platen operable to feed paper, a pawl for rotating said platen, a lever for operating said pawl, type driving hammers, 95
latches holding said hammers retracted, a device for releasing said latches, and manipulative mechanism settable to prevent said bar from releasing said latches and to prevent said lever from operating said pawl.

- 95 20. In a machine of the character described, a platen operable to feed paper, a pawl for rotating said platen, a lever for operating said pawl, type driving hammers, latches holding said hammers retracted, a 100
device for releasing said latches, manipulative mechanism settable to prevent said bar from releasing said latches and to prevent said lever from operating said pawl, and a latch holding said manipulative mechanism 105
in position to prevent effective operation of said bar and said lever.

- 110 21. In a machine of the character described, a platen, a ratchet wheel in connection with the platen, a rock shaft, a pawl supported by said rock shaft and movable into and out of engagement with said ratchet wheel to operate said platen, a lever for rocking said shaft, a spring for actuating said lever to turn said shaft in one 115
direction, a bell crank lever for actuating said first-named lever to turn said shaft in the opposite direction and to hold said first-named lever in one position, means for operating said bell crank lever, and a device 120
settable to prevent said first-named lever from operating to effect engagement of said pawl with said ratchet wheel when said bell crank lever is operated.

- 125 22. In a machine of the character described, a revoluble platen, a ratchet wheel in connection with the platen, a shaft, a pawl supported by the shaft, a lever for rocking the shaft to move the pawl into and out of engagement with the ratchet wheel 130

to rotate the platen, a spring for actuating said lever in one direction, a rock shaft, a device for moving said lever in opposition to said spring, connections from said rock shaft for operating said device to permit said spring to operate said lever and to move said lever to its starting point in opposition to said spring, and an element settable to limit movement of said lever to prevent the 10 pawl from becoming engaged with the ratchet wheel.

23. In a machine of the character described, a laterally movable paper carriage, a platen in said carriage, a ratchet wheel in 15 connection with the platen, a rock shaft supported in the carriage, a pawl operated by the rock shaft to engage with said ratchet wheel to turn the platen, a lever slidable upon the rock shaft and being operable to 20 rock said shaft, an operating shaft, connections operated by the operating shaft for actuating said lever in one direction and holding said lever in its normal position, a stop for limiting movement of said lever 25 to prevent rotation of the platen, and means for setting said stop in position to limit movement of said lever.

24. In a machine of the character described, a platen, platen rotating mechanism, type driving hammers, latches holding the hammers retracted, and a bar operable to release the latches from the hammers, in combination with a manipulative lever, connections operated by said lever, a 35 device operated by said connections to prevent operation of the platen rotating mechanism, and an additional device operated by said connections to prevent said bar from operating to release said latches.

40 25. In a machine of the character described, a platen, platen rotating mechanism, type driving hammers, latches holding the hammers retracted, and a bar operable to release the latches from the hammers, in combination with a manipulative 45 lever, connections operated by said lever, a device operated by said connections to prevent operation of the platen rotating mechanism, an additional device operated by said 50 connections to prevent said bar from operating to release said latches, and a device for holding said manipulative lever in position in which said connections will be held in operated position.

55 26. In a machine of the character described, a platen, platen rotating mechanism, type driving hammers, latches holding the hammers retracted, and a bar operable to release the latches from the hammers, in combination with a manipulative 60 lever, connections operated by said lever, a device operated by said connections to prevent operation of the platen rotating mechanism, an additional device operated by said 65 connections to prevent said bar from oper-

ating to release said latches, a device for holding said manipulative lever in position in which said connections will be held in operated position, adding mechanism, and means for releasing said device as an incident to operation of said adding mechanism. 70

27. In a machine of the character described, adding mechanism, a stop for preventing operation of said adding mechanism, recording mechanism operable with the adding mechanism, paper feed mechanism for feeding paper to the recording mechanism, means for operating the paper feed mechanism automatically as an incident to operation of the recording mechanism, hammers for cooperating with the recording mechanism, latches holding the hammers retracted, and a device operable to release said hammers automatically as an incident to operation of the recording mechanism, in combination with a manipulative device, and elements operated by said manipulative device to position said stop to permit operation of the adding mechanism, and to prevent operation of the operating means for the paper feed mechanism and to prevent said device from releasing said hammers. 80

28. In a machine of the character described, adding mechanism, a stop for preventing operation of said adding mechanism, recording mechanism operable with the adding mechanism, paper feed mechanism for feeding paper to the recording mechanism, means for operating the paper feed mechanism automatically as an incident to operation of the recording mechanism, hammers for cooperating with the recording mechanism, latches holding the hammers retracted, and a device operable to release said hammers automatically as an incident to operation of the recording mechanism, in combination with a manipulative device, elements operated by said manipulative device to position said stop to permit operation of the adding mechanism, and to prevent operation of the operating means for the paper feed mechanism and to prevent said device from releasing said hammers, and an element for holding said manipulative device in an adjusted position to cause the aforesaid elements to function as stated. 100

29. In a machine of the character described, adding mechanism, a stop for preventing operation of said adding mechanism, recording mechanism operable with the adding mechanism, paper feed mechanism for feeding paper to the recording mechanism, means for operating the paper feed mechanism automatically as in incident to operation of the recording mechanism, hammers for cooperating with the recording mechanism, latches holding the hammers retracted, and a device operable to release said hammers automatically as an incident to opera- 110 120 125 130

- tion of the recording mechanism, in combination with a manipulative device, elements operated by said manipulative device to position said stop to permit operation of 5 the adding mechanism, and to prevent operation of the operating means for the paper feed mechanism and to prevent said device from releasing said hammers, an element for holding said manipulative device in an 10 adjusted position to cause the aforesaid elements to function as stated, and means operated during the operation of the adding mechanism to release said holding element.
30. In a machine of the character described, the combination with paper feed mechanism, type driving hammers, latches for holding the hammers retracted, and a device for releasing the latches from the hammers, of a stop settable to prevent operation 15 of the paper feed mechanism and to prevent operation of said device which releases the latches, and means for setting said stop in position to prevent operation of said paper feed mechanism and said latch released device.
31. In a machine of the character described, the combination with paper feed mechanism, type driving hammers, latches for holding the hammers retracted, and a 20 device for releasing the latches from the hammers, of a stop settable to prevent operation of the paper feed mechanism and to prevent operation of said device which releases the latches, means for setting said 25 stop in position to prevent operation of said paper feed mechanism and said latch release device, and an element for holding said setting means in set position.
32. In a machine of the character described, the combination with paper feed mechanism, type driving hammers, latches holding the hammers retracted, and a device for releasing the latches from the hammers, of a stop for preventing operation of 30 the paper feed mechanism, an additional stop for preventing operation of the latch release device, a rock shaft, a connection from said rock shaft for operating said stops to position to prevent operation of 35 the paper feed mechanism and the latch release device, and a manipulative element for turning said rock shaft in a direction to set said stops.
33. In a machine of the character described, the combination with paper feed mechanism, type driving hammers, latches holding the hammers retracted, and a device for releasing the latches from the hammers, of a stop for preventing operation of 40 the paper feed mechanism, an additional stop for preventing operation of the latch release device, a rock shaft, a connection from said rock shaft for operating said stops to position to prevent operation of 45 the paper feed mechanism and the latch release device, and a manipulative element for turning said rock shaft in a direction to set said stops.
50. In a machine of the character described, a manipulative element for turning said rock shaft in a direction to set said stops, a latch for holding said manipulative device in the position to which it is operated, means for releasing said latch from said 55 manipulative device, and an actuator for moving said manipulative device to its starting point and thereby turning said rock shaft in the opposite direction to move said stops to position to permit operation of the 60 paper feed mechanism and the latch release device.
34. In a machine of the character described, the combination with type-carriers movable to and from recording position, a stop for preventing movement of the type-carriers to recording position, type on the type-carriers, paper feed mechanism operable as an incident to operation of the type-carriers to feed paper in line spacing, hammers for driving said type to record on the paper, latches holding the hammers retracted, and a device for releasing latches from the hammers corresponding to the type-carriers which operate, of a manipulative 65 lever, connections operated by said lever for moving said stop to position to permit the type-carriers to move to recording position, a device operated by said lever to prevent operation of the paper feed mechanism 70 during the time that said stop is in position to permit said type-carriers to move to recording position, and means operated by said lever to prevent operation of the latch release device; leaving said type-carriers free to operate while the paper feed mechanism remains inoperative and while the latches remain in engagement with the 75 hammers.
35. In a machine of the character described, the combination with type-carriers movable to and from recording position, a stop for preventing movement of the type-carriers to recording position, type on the type-carriers, paper feed mechanism operable as an incident to operation of the type-carriers to feed paper in line spacing, hammers for driving said type to record on the paper, latches holding the hammers retracted, and a device for releasing latches from the hammers corresponding to the type-carriers which operate, of a manipulative lever, connections operated by said lever for moving said stop to position to permit the type-carriers to move to recording position, a device operated by said lever to prevent operation of the paper feed mechanism during the time that said stop is in position to permit said type-carriers to move to recording position, means operated by said lever to prevent operation of the latch release device; leaving said type-carriers free to operate while the paper feed mechanism remains inoperative and while the latches remain in engagement with the hammers; and 80

adding mechanism operated under control of the type-carriers.

36. In a machine of the character described, the combination with a series of type-carriers movable to and from recording position, a stop for preventing movement of the type-carriers to recording position, type on the type-carriers, paper feed mechanism operable as an incident to operation of the type carriers to feed paper in line spacing, hammers for driving said type to record on the paper, latches holding the hammers retracted, a device for releasing the latches from the hammers corresponding to the type-carriers which operate, a series of adding pinions, racks associated with the series of type-carriers aforesaid for operating said adding pinions in adding and transferring operations, an abutment controlling the transfer operations of one of said racks, and a device operable to print a designation of the fact that such transfer operation had occurred, of a manipulative lever, and connections operated by said lever to move the said stop to position to permit said type-carriers to move to recording position, to prevent operation of the paper feed mechanism during the time that said stop is in position to permit said type-carriers to move to recording position, to prevent operation of said latch release device, to position said abutment to permit transfer operation of one of said racks, and to cause the operation of said printing device to print its designation.
37. In a machine of the character described, the combination with a series of type-carriers movable to and from recording position, a stop for preventing movement of the type-carriers to recording position, type on the type-carriers, paper feed mechanism operable as an incident to operation of the type-carriers to feed paper in line spacing, hammers for driving said type to record on the paper, latches holding the hammers retracted, a device for releasing latches from the hammers corresponding to the type-carriers which operate, a series of adding pinions, racks associated with the series of type-carriers aforesaid for operating said adding
- pinions in adding and transferring operations, and an abutment controlling the transfer operations of one of said racks, of a manipulative lever, connections operated by said lever for moving said stop to position to permit the type-carriers to move to a recording position, other connections operated by said lever for adjusting the said abutment to permit transfer operation of the corresponding rack, a device operated by said lever to prevent operation of the paper feed mechanism during the time said stop is in position to permit said type-carriers to move to recording position, and means operated by said lever to prevent operation of the latch release device; leaving said type-carriers free to operate while the paper feed mechanism remains inoperative and while the latches remain in engagement with the hammers.
38. In a machine of the character described, the combination with a series of type-carriers movable to and from recording position, a stop for preventing movement of the type-carriers to recording position, type on the type-carriers, mechanism for feeding paper to receive records from the type, hammers for driving the type to record on the paper, means for operating said hammers, a series of adding pinions, racks associated with the type-carriers for operating the adding pinions in adding and transferring operations, an abutment controlling the transfer operations of one of said racks, and mechanism for printing a designation of the fact that such transfer operation had occurred, of a manipulative lever, and connections operated by said lever for moving said stop to position to permit said type-carriers to move to recording position, and for preventing operation of the paper feed mechanism, and for preventing operation of said hammers, and for positioning said abutment to permit transfer operation of the rack controlled thereby, and for causing said printing device to print said designation to indicate the fact that such transfer operation had occurred.

HARRY LANDSIEDEL.
